US00D936036S

(12) **United States Design Patent** (10) **Patent No.:** **US D936,036 S**
(45) **Date of Patent:** **** Nov. 16, 2021**

(54) **HEADSET**

- (71) Applicant: **GN AUDIO A/S**, Ballerup (DK)
- (72) Inventors: **David Alden Jaques**, Durham, NH (US); **Thomas F. Terrien, Jr.**, Portsmouth, NH (US); **Kevin A. Batson**, Dover, NH (US); **William J. Blank, Jr.**, Hampton, NH (US)
- (73) Assignee: **GN AUDIO A/S**, Ballerup (DK)
- (**) Term: **15 Years**
- (21) Appl. No.: **29/741,293**
- (22) Filed: **Jul. 10, 2020**

Related U.S. Application Data

- (62) Division of application No. 29/673,353, filed on Dec. 13, 2018, now Pat. No. Des. 900,056.
- (51) **LOC (13) Cl.** **14-01**
- (52) **U.S. Cl.**
USPC **D14/205**; D14/223

(57) **CLAIM**

The ornamental design for a headset, as shown and described.

DESCRIPTION

FIG. 1 is a perspective view of a headset showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a headset showing our new design;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The features shown in broken lines depict environmental subject matter only and form no part of the claimed design.

1 Claim, 14 Drawing Sheets
